UNITED STATES PATENT OFFICE.

JOSEPH J. MICHAUD AND GUSTA SOCIA, OF ISLAND FALLS, MAINE.

BUCKSAW-FRAME TIGHTENER.

Application filed April 20, 1928. Serial No. 271,590.

The present invention relates to improvements in buck saw frame attachments and has reference more particularly to a tightening means for association with the upper ends of 5 the side bars of the frame.

One of the important objects of the present invention is to provide a buck saw frame 10 tightener wherein the tightener can be readily and easily adjusted to permit the proper tension to be obtained whereby to hold the saw blade taut.

A further object of the invention is to provide a buck saw frame tightener which can be readily and easily attached on the frame without necessitating any alterations of the frame, the tightener being further simple in construction, inexpensive, strong and durable and further well adapted to the purpose for which it is designed.

20 Other objects and advantages of the invention will become apparent during the course of the following description taken in connection with the accompanying drawing.

In the accompanying drawing wherein like reference characters indicate corresponding parts throughout the same:

Figure 1 is a fragmentary side elevation of a conventional buck saw frame showing our improved tightener attached thereon.

30 Figure 2 is a top plan view of the tightening means, and

Figure 3 is a sectional view taken approximately on the line 3—3 of Figure 1 looking in the direction of the arrow.

35 In the drawing wherein for the purpose of illustration is shown the preferred embodiment of our invention, the numerals 1 and 2 designate the upper portions of the usual side bars of a buck saw frame which is of the conventional construction, the saw blade and the handle associated with the lower end of one side bar, not being shown.

Our improved tightening device includes a 45 pair of coacting tightening members designated generally by the numerals 3 and 4 respectively. The member 3 consists of an elongated flat bar 5 that is formed at its inner end with a yoke 6 for a purpose to be presently described. A piece of wire bent to form an elongated loop 7 has its free end pivotally attached to the outer end of the bar 5, as at 8, and this loop 7 is adapted to be disposed over the upper end of the side bar 1 in the manner as shown in Figure 1.

50 The coacting tightening member 4 comprises a pair of bar members 9 and 10, respec-

tively, that are disposed in parallel spaced relation with respect to each other through the medium of the spacing members 11, and appropriate fastening means extend through the spaced bars and the spacing members as clearly shown in Figure 2. The tightening member 4 is of greater length than the member 3, and a loop 12 which is identical in construction with the loop 7 is pivotally secured to the outer end of the member 4 as at 13, and is adapted to be disposed over the upper end of the side bar 2, as clearly shown in Figure 1. The inner end portions of the bars 9 and 10 comprising the tightening members are 70 formed with a series of spaced registering openings shown at 14. Furthermore certain of the spacing members 11 are formed in their upper edges with the notches 15, and the upper edges of the side bars are formed with 75 communicating notches shown at 16.

A lever 17 has its upper end offset for disposition through the yoke 6 formed on the inner end of the bar 5, and a pivot pin 18 extends through the sides of the yoke and the 80 adjacent portion of the offset upper end of the lever 17. The upper end of said lever is pivotally secured between the side bars 9 and 10 of the member by passing a bolt 19 through predetermined registering openings 14 85 formed in the side bars and through an opening formed in the upper extremity of the lever and the thumb nut 20 is threaded on the threaded end of the bolt. In this manner, an operative connection is provided between the 90 inner opposed ends of the tightening members 3 and 4.

The intermediate portion of the lever 17 is slightly offset as at 21, and a strip 22 has its end portions bent inwardly for attachment to the inner side of the lever 17 directly adjacent the offset portion 21 and the offset portion 21 cooperates with the strip 22 to provide a housing for the lower end of a rack bar 23, the lower end of said rack bar being pivotally secured between the offset portion 21 and the strip 22 as at 24.

One edge of the rack bar is formed with the ratchet teeth 25 and the free upper end of this pivotally mounted rack bar is disposed upwardly between the side bars 9 and 10 of the tightening member 4, and the ratchet teeth cooperate with the notches 15 to retain the tightening members in their properly adjusted position.

105 It is readily obvious that when the lower end of the lever 17 is swung upwardly, the

ratchet bar 23 may be raised and when the lever is moved upwardly, the same will cause the members 3 and 4 to move inwardly toward each other, thereby drawing inwardly on the 5 upper ends of the side bars to properly tension the saw blade that is secured between the lower ends of the bars of the buck saw frame in the usual manner. The ratchet teeth 25 will cooperate with the notched members carried by the tightening member 4 to properly 10 retain the side bars of the buck saw frame in their adjusted relation.

It will thus be seen from the foregoing description, that we have provided a buck saw 15 frame tightener that can be readily and easily attached on the frame of a conventional buck saw and by reason of its simplicity, the tightener can be efficiently actuated, and the same will not in any way interfere with the use of 20 the buck saw when attached to the upper portions of the side bars of the frame.

Furthermore, a buck saw frame tightener of the above mentioned character can be manufactured at a very low cost and will be strong 25 and durable.

While we have shown the preferred embodiment of our invention, it is to be understood that minor changes in the size, shape 30 and arrangement of parts may be resorted to without departing from the spirit of the invention and the scope of the appended claim.

Having thus described the invention, what we claim as new and desire to secure by Letters Patent is:—

In combination with the side bars of a buck saw frame, of a tightening device therefor including a pair of coacting tightening members, one of said members comprising a bar formed at its inner end with a yoke, a loop carried by the outer end of said bar for engagement over the upper end of one of the side bars, the other member including a pair of spaced bars secured together, a loop carried by the outer ends of said bars for engagement over the upper end of the other side bar, a lever pivotally secured at its upper end between the spaced bars adjacent the inner ends thereof, said lever extending downwardly through the yoke on the inner end of the first mentioned bar and being pivotally secured therein whereby said coacting tightening members will be moved simultaneously in opposite directions upon the actuation of the lever, means for locking said tightening members in an adjusted position, said last mentioned means comprising a ratchet bar pivoted at its lower end to the intermediate portion of the lever, the upper end of said bar extending upwardly between the spaced bars of one of the tightening members, and a notched element secured between said spaced bars with which the teeth of the ratchet bar cooperate.

In testimony whereof we affix our signatures.

JOSEPH J. MICHAUD.
GUSTA SOCIA.
